FIRING MECHANISM FOR AUTOMATIC FIREARMS

Marriner A. Browning, Ogden, Utah, assignor to
 J. M. & M. S. Browning Company, Ogden,
 Utah, a corporation of Utah

Original application April 10, 1934, Serial No.
 719,862. Divided and this application March
 19, 1935, Serial No. 11,791

15 Claims. (Cl. 89—27)

One object of the invention is to provide an improved hammer mechanism which is controlled directly by the main operating slide so as to insure the closing of the breech before firing occurs.

Another object of the invention is to provide an improved retarding mechanism whereby the gun may be caused to operate at a slower speed than it otherwise would.

10 This present application constitutes a division of my copending application for Automatic firearm, Serial No. 719,862, filed April 10, 1934, which said co-pending application was issued as Patent No. 2,093,704 on September 21, 1937.

15 In the accompanying drawings I have shown the embodiment of the invention which I now deem preferable, but it will be understood that the drawings are intended for illustrative purposes only and are not to be relied upon as limiting or defining the scope of the invention, the 20 claims forming a part of this specification being relied upon for that purpose.

Of the drawings:

Fig. 1 is a side view of a firearm embodying 25 the invention.

Fig. 2 is an enlarged fragmentary view of the rear portion of the firearm, this view being partly a side view and partly a longitudinal sectional view.

30 Fig. 3 is a view similar to Fig. 2 but showing the parts in different relative positions.

Fig. 4 is a transverse sectional view taken along the line 4—4 of Fig. 3.

35 Fig. 5 is a fragmentary view similar to a rear portion of Figs. 2 and 3, and showing the retarding mechanism in an intermediate position.

Fig. 6 is a view similar to Fig. 5, but showing the retarding mechanism in its hammer releasing position.

40 Fig. 7 is a view similar to Fig. 5, but showing the retarding mechanism reset by a cam on the operating slide.

Fig. 8 is an enlarged fragmentary view taken along the line 8—8 of Fig. 6.

45 Fig. 9 is a cross sectional view taken on the line 9—9 of Fig. 8.

Fig. 10 is an enlarged fragmentary longitudinal sectional view taken along the line 10—10 of Fig. 8.

50 Fig. 11 is a view similar to Fig. 10 but showing the parts in different relative positions.

Referring to the drawings, 1 represents as an 55 entirety the main breech casing which is generally rectangular in section as shown in Fig. 4.

As shown the casing is formed from a single piece

of steel although I do not necessarily limit myself to this integral construction. The portion 1^a of the casing is formed to receive the rear end of a barrel 2. Behind the portion 1^a are two main side walls 1^b, 1^b connected near the center by an integral cross member 1^c. An opening 1^d is provided at the front of the cross member 1^c, which opening is normally closed by a pivoted cover 3 held by a releasable latch 3^a. An opening is provided at the rear of the cross member, which opening is closed by a plate 4. The bottom of the casing is normally closed by separate plates 5 and 6. The rear of the casing is normally closed by a plate 7 flanged at its sides and having ribs (not shown) adapted to enter grooves formed in the side walls 1^b, 1^b. A suitable latch 7^b serves to normally hold the end plate 7 in place. Carried by the plate 7 at opposite sides thereof are two brackets 8, 8 carrying handles 9, 9.

The casing 1 is provided with an integral extension 1^e which extends forward underneath the barrel. This extension is hollow and it serves to engage and retain a piston tube 16. At its forward end the tube 16 is connected with, and supported by, the barrel. Longitudinally movable along the bottom of the main casing is an operating slide 27, this slide being connected with a piston 29 and a piston rod 28 positioned within the piston tube 16. A cylinder 31 is provided in the forward end of the tube 16, and the piston accurately fits the said cylinder. A gas passage extends from the bore of the barrel to the cylinder, to enable the gases of explosion to enter the cylinder and act upon the piston to force it rearward.

For returning the slide in the forward direction after having been moved rearward by the piston and piston rod, there is provided an action spring 32 supported upon and guided by a rod 33. Preferably the spring and rod 32 and 33 extend into a hollow buffer 34 carried by the rear plate 7. The spring at its rear end abuts against a head 35 detachably secured in place in the buffer. The spring at its forward end extends into an aperture in the slide 27 and abuts against a shoulder 36. A hole 36^a provides clearance for the rod 33 when the slide is in its rear position. The slide 27 serves to operate the feeding, loading and firing mechanisms of the gun.

Extending transversely through the casing below the rear portion of the barrel is a cartridge feed channel 37 adapted for the reception of a cartridge belt such as A. Transversely movable below the feed channel 37 is a feed slide 39, 55

which is actuated by means of the operating slide 27. As shown, the main portion of the feed slide is below the operating slide, and in this case the operating slide has a cam groove in its lower face 5 into which projects a pin carried by the feed slide. The shape of the groove is such that the feed slide is reciprocated transversely as the operating slide reciprocates longitudinally. The feed slide carries a pawl which engages the cartridge belt to bring a new cartridge into a position below the barrel at each actuation of the operating slide.

Preferably the operating slide 27 and the parts associated therewith are removable from the firearm at the rear thereof. To effect such removal it is necessary first to remove the spring 32 and the rod 33 and to then remove the end plate 1 with the parts carried thereby. The slide is then substantially free to be withdrawn in the rearward direction, except for the fact that the pin on the feed slide must be disengaged from the groove in the operating slide.

The firearm is provided with a reciprocating breech bolt 45 which is guided between the side walls 1^b, 1^b of the casing. The breech bolt is operated and controlled by mechanism operated by the slide 27, this mechanism being similar to that disclosed in Patent No. 1,293,022 to John M. Browning. As shown in Fig. 3 the breech bolt 45 is connected with the slide 27 by means of two links 46 and 47 pivotally connected with each other at 48. The link 46 is pivotally connected with the breech bolt at 49 and the link 47 is pivotally connected with the slide at 50. When the slide 27 is in its rear position as shown in Fig. 3, the two links 47 and 48 are held substantially in alignment in the relative positions shown. A lug 47^a on the link 47 engages the link 46 to prevent downward movement beyond the position shown.

When the slide 27 moves forward under the influence of the action spring 32 the two links 46 and 47 and the breech bolt 45 move in unison with it until the breech bolt nearly reaches its forward position, the link 46 being then approximately in register with the opening 1^d in the top wall of the casing. At or about the time that the link comes into register with the opening the curved portion 46^b of the link 46 engages two cams 51 projecting inward from the respective side walls 1^b, 1^b of the casing. In the drawings only the cam on the left hand side is clearly shown, but it will be understood that there is a similar cam on the right hand side. These cams 51 cooperate with the curved portion 46^b of the link 46 to force the link upward into the opening 1^d, the rear end portion of the link abutting against the rear wall of the opening as clearly shown in Fig. 2. In the meantime the slide 27 has continued its forward movement, thus bringing the link 47 into a substantially upright position. With the parts in the position shown and described, the breech bolt is firmly locked in its forward or breeched position and is well adapted to resist the recoil action incident to firing. Following firing the slide 27 is moved rearward by the action of the gases of explosion in the manner already described, the link 47 serving first to draw the link 46 downward out of locking position and then to move the link 46 and also the bolt 45 rearward to the positions shown in Fig. 3.

Reference has already been made to the fact that the slide 27 can be removed through the rear of the casing. It will be understood that the breech bolt 45 and the links 46 and 47 are simi-

larly removable, all of these parts being removable as a unit.

A firearm incorporating the present invention is intended to be used with cartridges having annular grooves in the heads thereof, and the front end of the breech bolt is provided with vertical ribs 52, 53 which cooperate to form a vertical groove for receiving and retaining the heads of the cartridges. When the breech bolt is in its forward position as shown in Fig. 2 the head of the cartridge which is in central position in the feed channel 37 is vertically below the groove in the front of the breech bolt. For withdrawing the cartridge from the feed channel and lifting it into proper relationship to the breech bolt there is provided an extractor 54. This extractor is provided with a pivot pin 55 which fits a transverse pivot opening in the breech bolt, the extractor thus moving bodily rearward and forward as the breech bolt moves. The extractor 54 is provided with a transversely extending tooth 56 which is so shaped and positioned as to enter the groove in the cartridge when the breech bolt and the extractor are in their forward positions as shown in Fig. 2.

A suitable cam mechanism is provided for controlling and guiding the relative movements of the extractor, but as this cam mechanism constitutes no part of the present invention and is fully disclosed in my said application No. 719,862, 30 it is not necessary to include a detailed description of it in this present specification. It is sufficient to say that when the breech bolt moves rearward the extractor moves rearward and upward, causing the cartridge to be extracted and 35 then lifted into alignment with the chamber in the barrel. As the breech bolt returns in the forward direction, the cartridge is inserted into the chamber and the extractor is again moved downward into position to engage another cartridge in the feed channel.

A second extractor 69 is provided for extracting the empty shell from the chamber as the breech bolt moves rearward. This extractor serves in cooperation with the ejector to eject the empty shell from the ejection opening 76 in the right wall of the casing.

Mounted in a hole in the breech bolt 45 is a firing pin 78 capable of limited longitudinal movement and having an enlarged head 78^a at the rear. The firing pin is provided with a lug 79 which projects upward through a suitable slot in the breech bolt and when the parts are in their rearward positions, as shown in Fig. 3, the lug 79 projects into an opening 80 in the link 46. 55 The forward edge of the opening 80 is curved and serves as a cam surface to engage the lug 79 and thus move the firing pin 78 relatively rearward during rearward movement of the breech bolt. The lug 79 serves to positively prevent the firing pin from coming into engagement with the cartridge except when the breech bolt is in its forward position, as shown in Fig. 2.

For actuating the firing pin 78 there is provided a hammer 81 pivoted at 82 in a recess in the top plate 4. Fig. 3 shows the hammer in cocked position, it being so held by a sear 83 pivoted to the plate 4 at 84 and engaging a shoulder 81^a extending transversely of the hammer. The sear 83 is biased toward its engaged position by a spring 85. The hammer is biased toward its firing position by means of a link 86 pivoted to the hammer at 87. The link is supported and guided at the rear by a lug 88 through which it extends. A spring 89 surrounds the link 75

and abuts against the lug 88. The forward end of the spring abuts against a shoulder on the link.

The hammer is cocked by engagement with the slide 27 and its associated parts as they move rearward from the position shown in Fig. 2 to the position shown in Fig. 3. To facilitate cocking the slide 27 is provided with two upward projecting lugs 90, 90 which initially engage the hammer to start the cocking movement thereof. Subsequently the hammer is engaged by the upward extension 46^a on the link 46 which serves to move it to its fully cocked position, as shown in Fig. 3.

In order that the hammer, when released, may actuate the firing pin there is provided an intermediate striker 91 carried by the link 47. This striker is in the form of a rod slidably mounted in a hole in the link and having longitudinal movement therein, such movement being limited by a pin 92 extending transversely of the link and extending through a notch in the rod or striker. The relationship of the parts is such that when the breech bolt is in its forward position the striker 91 is in engagement with the enlarged rear end portion 78^a of the firing pin 78. When the hammer is released in the manner to be presently described it moves from the position shown in Fig. 3 to the position shown in Fig. 2, engaging the striker and driving it forward to actuate the firing pin and to thus cause the cartridge to be fired.

The lower right hand portion of the sear 83 is cut away to provide a notch for a sear operating lever 93 as shown in Fig. 9. This lever is clearly shown in Fig. 2, but a part of it is omitted from Fig. 3 in order that the sear itself may be more clearly shown. The operating lever 93 is preferably pivoted coaxially with the hammer 81 and the forward end thereof is in engagement with the downward facing top wall of the before-mentioned notch in the sear. The tail portion 93^a of the lever is adapted to engage the top wall of the casing, as shown in Fig. 3, so as to limit movement in the clockwise direction. For actuating the lever 93 and for thus in turn actuating the sear 83 there is provided an upward projection 94 at the rear of the slide 27 and at the right hand side thereof, as shown in Figs. 2, 3, 5 and 6. When the parts reach their forward positions as shown in Figs. 2, 5 and 6, the extension 94 on the slide 27 is forced underneath the forward portion of the lever 93, thus forcing the said forward portion upward and moving the sear 83 in the counter-clockwise direction so as to release the hammer.

For holding the slide 27 in its rear position as shown in Fig. 3 there is provided a second sear 95 pivoted to the bottom plate 5. This sear is spring pressed upward and engages a notch 96 in the bottom of the slide. Carried by the rear plate 7 is a manually operable trigger 97 having a tail portion which projects forward through an opening in the plate and is adapted to engage the sear 95. A spring pressed plunger 98 tends to hold the trigger in its rearward inoperative position.

In initially loading the gun in order to start firing it is ordinarily necessary to operate the mechanism of the gun by hand in order to withdraw the first cartridge from the belt and transfer it into the position shown in Fig. 3. For this purpose there is provided a handle 99 extending through a slot 100 in the right side wall of the casing and fitting a hole 101 in the slide 27. The slot 100 is enlarged at its rear end and the handle

99 is so formed that it can be removed only when in register with the enlarged rear end of the slot.

When the trigger 97 is pressed forward the sear 95 is disengaged from the slide 27 and the slide moves forward, causing the links 46 and 47 and the breech bolt 45 to assume the positions shown in Fig. 2. When these positions are reached the projection 94 on the slide 27 releases the hammer 81 in the manner already described, thus actuating the firing pin and causing firing. Thereupon the gases of explosion enter the cylinder 31 and drive the piston 29 rearward, thus moving the slide 27 rearward and causing the various parts of the gun to assume the relative positions shown in Fig. 3. During this rearward movement a new cartridge is extracted from the belt and the shell of the exploded cartridge is ejected in the manner already described. If, in the meantime, the trigger 97 has been released and permitted to resume its normal position, the slide is caught and held by the sear 95 and no further firing takes place. If, however, the trigger 97 is held in its forward firing position the parts immediately again move forward to the firing position shown in Fig. 2 and firing again occurs. Thus volley firing may be continued so long as the trigger 97 is held and so long as the supply of cartridges in the belt is not exhausted.

In addition to the parts already described the gun may also be provided with a means for retarding the rate of fire. This means may be included or omitted as desired.

As shown, particularly in Figs. 8, 10 and 11, there is provided an auxiliary sear 102 mounted coaxially with the sear 83 and biased toward its engaged position by a spring 103. The sear 102 is positioned at the left side of the gun and is adapted to engage the same shoulder 81^a in the hammer that is engaged by the sear 83. For disengaging the sear 102 from the shoulder 81^a there is provided a slide or sear release 104 at the left side of the gun, this slide being guided in part by the pivot pin at 82 and in part by a pin 105 projecting inward from the left side of the recess in the top plate 4. When the slide 104 is in its rearward position as shown in Fig. 11 the sear 102 engages the shoulder 81^a and prevents movement of the hammer even though the sear 83 be released in the manner heretofore described. If the slide 104 be moved forward to the position shown in Fig. 10 an extension 104^a on the slide engages the sear to disengage it and thus release the hammer.

Secured to the top plate 4 is a bracket 106, shown in Figs. 2, 3, 5, 6 and 7, this bracket being U-shaped and carrying two pivot pins 106^a and 107. Mounted on the pivot pin 106^a is a ratchet wheel 108 and an escapement wheel 109, these two wheels being connected together for movement in unison. Mounted on the pivot pin 107 is an escapement weight 110 having teeth thereon which engage the teeth on the wheel 109. The teeth on the escapement weight are so related to the teeth on the wheel that the weight is forced to oscillate as the wheel is turned. Thus the weight offers resistance to the turning of the wheel.

Pivotedly mounted at 111 is a lever 112 which is biased for movement in the counter-clockwise direction by means of a spring 113. Pivotedly connected at 114 to the lever 112 is a ratchet arm 115 having teeth thereon adapted to engage with the teeth of the ratchet wheel 108. A spring 116 serves to bias the arm 115 in the clockwise direction, thus tending to hold it in engagement with

the wheel. The lever 112 is positioned at the left side of the casing and is adapted to be engaged and reset by a cam surface 117 on the slide 27. Thus when the slide moves rearward 5 the lever 112 is moved or reset in the clockwise direction to the position shown in Figs. 2 and 7. In so moving the teeth on the arm 115 may snap over the teeth on the wheel 108 without causing the wheel to rotate.

10 It will be seen that the lever 112 after having been moved by the cam 117 to the position shown in Fig. 7, tends to move in the counter-clockwise direction, but it can so move only by causing corresponding rotation of the ratchet wheel 106. 15 The ratchet wheel is restrained from rapid movement by reason of its connection with the escapement wheel 109. Thus the lever 112 is permitted to move in the counter-clockwise direction, but only at a relatively slow rate determined by the 20 action of the escapement weight 110.

25 The lever 112 is provided with a forward extension 112^a which is adapted to engage the rear edge of the slide 104. Thus as the lever moves relatively slowly in the counter-clockwise direction, the extension 112^a engages the slide 104 so that the slide is moved forward to release the sear 102. Fig. 11 shows the extension 112^a just coming into engagement with the slide, the slide, however, not yet having been moved.

30 From the foregoing description it will be apparent that when the main operating slide 27 moves rearward to the position shown in Figs. 3 and 7, the lever 112 is moved in the clockwise direction, to the position shown in the same figures. If the trigger 97 is maintained in its depressed position the slide 27 with its associated parts immediately moves forward to the position shown in Figs. 2, 3 and 6, thus releasing the main sear 83 in the manner already described. Firing, 40 however, does not immediately occur for the reason that the hammer is still held by the auxiliary sear 102. However, as soon as the cam surface 117 on the slide 27 moves out of the way of the lever 112 the said lever starts to move 45 relatively slowly in the counter-clockwise direction, the extension 112^a thereof eventually engaging the slide 104 as shown in Figs. 5 and 11. The slide 104 is then pushed forward to release the sear 102 and thus permits the hammer to 50 move and cause firing as shown in Fig. 6. With this retarding mechanism in use the rate of fire may be very much less than it otherwise would be, the amount of decrease in the rate being in large measure dependent upon the size of the 55 escapement weight 110.

It will be observed that when the retarding mechanism is used the main sear 83 normally has no control of the firing, but the said sear nevertheless serves as a safety means to prevent 60 premature release of the hammer in the event of any jamming or malfunctioning of the gun. The sear 83 prevents release of the hammer before the breech bolt reaches its forward locked position.

65 The retarding mechanism serves not only to decrease the rate of fire but also to increase accuracy. The momentary delay between the closing of the breech and the firing of the cartridge permits vibrations to expend themselves so that 70 the gun is in a static condition at the instant of firing.

In order that the retarding mechanism may be rendered inoperative when not required, there is preferably provided a transverse shaft or pin 75 118 adapted to be oscillated by means of a lever

119 on the exterior of the casing. Secured to the pin 118 is a finger or projection 120 which is projectable into the arc of movement of the lever 112, as shown in Fig. 10, to positively maintain it in its rearward or inoperative position. Associated with the finger 120 is a projection 121 which engages an extension 104^b on the slide 104 to hold the slide in its forward position and to thus hold the sear 102 in its inoperative position, as also shown in Fig. 10. With the parts in this position the retarding mechanism is entirely inoperative and the action of the gun is exactly the same as it would be if the said mechanism were not provided.

10 By moving the lever 119 in the counter-clockwise direction the finger 120 and the projection 121 can be moved to the positions shown in Fig. 11, thus freeing the retarding mechanism and permitting it to operate in the manner which has already been fully described.

20 What I claim is:

1. An automatic firearm comprising in combination, a barrel, a breech casing carrying the barrel, a longitudinally movable breech bolt in the casing, an operating slide automatically and rectilinearly movable rearward upon firing and biased for automatic return movement to its forward position, pivoted link mechanism connecting the breech bolt with the slide and enabling the latter to move the former, automatic means associated with the bolt and serving during rearward and forward movements thereof to feed cartridges successively to the chamber of the barrel, a firing pin carried by the bolt and movable longitudinally relatively thereto, a hammer pivoted to the casing and serving when released to actuate the firing pin, a sear for holding and releasing the hammer, means for cocking the hammer during rearward movement of the slide, and an upward projection on the slide for moving the sear to release the hammer when the slide reaches its forward position.

2. An automatic firearm comprising in combination, a barrel, a breech casing carrying the barrel, a longitudinally movable breech bolt in the casing, an operating slide automatically and rectilinearly movable rearward upon firing and biased for automatic return movement to its forward position, pivoted link mechanism connecting the breech bolt with the slide and enabling the latter to move the former, automatic means associated with the bolt and serving during rearward and forward movements thereof to feed cartridges successively to the chamber of the barrel, a firing pin carried by the bolt and movable longitudinally relatively thereto, means on the firing pin engageable by the pivoted link mechanism for retracting the firing pin relative to the bolt, a hammer pivoted to the casing and serving when released to actuate the firing pin, a sear for holding and releasing the hammer, means for cocking the hammer during rearward movement of the slide, and means on the slide for moving the sear to release the hammer when the slide reaches its forward position.

3. An automatic firearm comprising in combination, a barrel, a breech casing carrying the barrel, a longitudinally movable breech bolt in the casing, an operating slide automatically movable rearward upon firing and then automatically returning to its forward position, link mechanism connecting the breech bolt with the slide and enabling the latter to move the former, automatic means associated with the bolt and serving during rearward and forward movements thereof to feed

cartridges successively to the chamber of the barrel, a firing pin carried by the bolt and movable longitudinally relatively thereto, a hammer pivoted to the casing, a sear for holding and releasing the hammer, and a striker carried by the link mechanism and interposed between the hammer and the firing pin when the bolt is in its forward position, the said striker thus enabling the hammer when released to actuate the firing pin.

5. An automatic firearm comprising in combination, a barrel, a breech casing carrying the barrel, a longitudinally movable breech bolt in the casing, a longitudinally movable operating slide adjacent the bolt which upon firing automatically moves rearward to a greater extent than the bolt, two connected operating links pivotally connected respectively with the bolt and with the slide, the bolt connected link when the bolt and slide are in forward positions serving to lock the bolt and the slide connected link upon rearward movement of the slide serving to effect unlocking and then to move the other link and the bolt rearward, automatic means associated with the bolt and serving during rearward and forward movements thereof to feed cartridges successively to the chamber of the barrel, a firing pin carried by the bolt and movable longitudinally relatively thereto, a hammer pivoted to the casing, a sear for holding and releasing the hammer, and a striker carried by the slide connected link and interposed between the hammer and the firing pin when the bolt is in its forward position, the said striker thus enabling the hammer when released to actuate the firing pin.

35. 5. In an automatic firearm, the combination of a breech casing, firing means, sear mechanism for holding the firing means in non-firing position, actuating means for moving the sear mechanism to inoperative position, means for positively preventing said actuating means from moving the sear mechanism, and a second means for moving the sear mechanism to inoperative position and for holding the same in said position.

40. 6. In an automatic firearm, the combination of a breech casing, a sear, a sear release movable to a sear releasing position, means to move the sear release to releasing position, means for preventing the first means from moving the sear release, and a second means for moving the sear release to releasing position and for holding the same in said position.

45. 7. In an automatic firearm, the combination of a breech casing, a sear, a sear release movable to a sear releasing position, a lever pivoted to the casing and engageable with the sear release to move the same to releasing position, means mounted on the casing projectable into the arc of movement of the lever for preventing engagement of the same with the sear release, and means for 50 moving the sear release to releasing position and for holding the same in said position.

55. 8. In an automatic firearm, the combination of a breech casing, a sear, a sear release movable to a sear releasing position, a lever pivoted to the casing and having a projection thereon for engagement with the sear release to move the same to releasing position, and means pivotally mounted on the casing having two projections thereon, one for engagement with the projection on the lever for preventing engagement of the latter with the sear release and the other for engagement with the sear release to slide the same to releasing position and for holding the same in said position.

70. 9. In an automatic firearm, the combination of

a breech casing, a sear, a sear release movable to a sear releasing position, means to move the sear release to releasing position, means for controlling the rate of fire connected with said first named means to move the same to cause the sear release to be moved to releasing position, means for preventing the first means from moving the sear release, and a second means for moving the sear release to releasing position and for holding the same in said position.

10. 10. In combination in an automatic firearm, a barrel, a breech casing carrying the barrel, a longitudinally movable breech bolt in the casing, a longitudinally movable operating slide adjacent the bolt which upon firing automatically moves rearward to a greater extent than the bolt, two connected operating links pivotally connected respectively with the bolt and with the slide, the bolt connected link when the bolt and slide are in forward positions serving to lock the bolt and the slide connected link upon rearward movement of the slide serving to effect unlocking and then to move the other link and the bolt rearward, a firing pin on the bolt longitudinally movable relatively thereto, a hammer pivoted to the casing and serving when released to actuate the firing pin, a sear for holding the hammer, means for cocking the hammer during rearward movement of the slide, means for moving the sear to release the hammer after a predetermined interval of time following the movement of the bolt to its forward position, and means dependent on the rearward movement of the slide for resetting the sear moving means.

11. 11. In combination in an automatic firearm, a barrel, a breech casing carrying the barrel, a longitudinally movable breech bolt in the casing automatically movable rearward upon firing and biased for automatic return movement to its forward position, a firing pin carried by the bolt and movable longitudinally relatively thereto, a hammer pivoted to the casing and serving when released to actuate the firing pin, a sear for holding the hammer, means for cocking the hammer during rearward movement of the bolt, a longitudinally movable slide for moving the sear to release the hammer, and spring means for automatically moving the slide in the sear releasing direction to release the sear after a predetermined interval of time following the movement of the bolt to its forward position.

12. 12. In combination in an automatic firearm, a barrel, a breech casing carrying the barrel, a longitudinally movable breech bolt in the casing automatically movable rearward upon firing and biased for automatic return movement to its forward position, automatic means associated with the bolt and serving during rearward and forward movements thereof to feed cartridges successively to the chamber of the barrel, a firing pin carried by the bolt and movable longitudinally relatively thereto, a hammer pivoted to the casing and serving when released to actuate the firing pin, a sear for holding the hammer, means for cocking the hammer during rearward movement of the bolt, a longitudinally movable slide for moving the sear to release the hammer, means for moving the slide in the sear releasing direction to release the sear after a predetermined interval of time following the movement of the bolt to its forward position, and a single manually operable means for holding the slide moving means in an inoperative position and for holding the slide in the position corresponding to the releasing position of the sear.

13. 13. In combination in an automatic firearm, a barrel, a breech casing carrying the barrel, a lon-

- 5 longitudinally movable breech bolt in the casing automatically movable rearward upon firing and biased for automatic return movement to its forward position, a firing pin carried by the bolt and

- 5 movable longitudinally relatively thereto, a hammer pivoted to the casing and serving when released to actuate the firing pin, a main sear for holding the hammer, an auxiliary sear for also holding the hammer, means for cocking the hammer during rearward movement of the bolt, means for moving the main sear to its hammer releasing position, which means acts immediately upon the movement of the bolt to its forward position, and means for normally moving the auxiliary sear to its hammer releasing position after a predetermined interval following the movement of the bolt to its forward position.
14. In combination in an automatic firearm, a barrel, a breech casing carrying the barrel, a longitudinally movable breech bolt in the casing, a longitudinally movable operating slide adjacent the bolt which upon firing automatically moves rearward to a greater extent than the bolt, two connected operating links pivotally connected respectively with the bolt and with the slide, the bolt connected link when the bolt and slide are in forward positions serving to lock the bolt and the slide connected link upon rearward movement of the slide serving to effect unlocking and then to move the other link and the bolt rearward, a firing pin on the bolt longitudinally movable relatively thereto, a hammer pivoted to the casing and serving when released to actuate the firing pin, a main sear for holding the hammer, an auxiliary
- 5 10 15 20 25 30
- 5 sear for also holding the hammer, means for cocking the hammer during rearward movement of the bolt, means for moving the main sear to its hammer releasing position, which means acts immediately upon the movement of the bolt to its forward position, means for normally moving the auxiliary sear to its hammer releasing position after a predetermined interval following the movement of the bolt to its forward position, and means on the operating slide and acting during rearward movement thereof for resetting the means for moving the auxiliary sear.
15. In combination in an automatic firearm, a barrel, a breech casing carrying the barrel, a longitudinally movable breech bolt in the casing automatically movable rearward upon firing and biased for automatic return movement to its forward position, a firing pin carried by the bolt and movable longitudinally relatively thereto, a hammer pivoted to the casing and serving when released to actuate the firing pin, a main sear for holding the hammer, an auxiliary sear for also holding the hammer, means for cocking the hammer during rearward movement of the bolt, means for moving the main sear to its hammer releasing position, which means acts immediately upon the movement of the bolt to its forward position, means for normally moving the auxiliary sear to its hammer releasing position after a predetermined interval following the movement of the bolt to its forward position, and means for moving the auxiliary sear to an inoperative position and for holding the same in said position.

MARRINER A. BROWNING.
